The Patriotic Sewing Machine Company of State of N. J.
Letters Patent No. 2473. Dated Oct. 2, 1866

Design for a Sewing Machine

The Schedule referred to in these Letters Patent, and making part of the same.

To all whom it may concern:

Be it known that A. Joseph Bond, junior of Newark, Essex County New Jersey, have originated and designed a new pattern of shape and form for a Sewing Machine, of which the following is a full, clear and exact description, reference being had to the accompanying photograph thereof, making a part of this Specification.

A, is the body or frame of the Machine. — B, the cloth plate. — C, the vibrating middle arm. — D, the stationary arm. E, the presser foot, or cloth holder. — F, the pulley wheel by which motion is given to the Machine and G, & G, are the points on which the vibrating arm moves.

The whole design of the Machine combines great strength and beauty, and keeps out of view the operating parts of the machinery, all which is sufficiently shown by the Photograph without a more minute description.

What I claim and desire to secure by Letters Patent is,
The Design for a Sewing Machine as herein set forth and shown
Witnesses

George H. Collins.
